Primary Examiner — Adir Aronovich*Assistant Examiner* — Ramzi Almatrahi(74) *Attorney, Agent, or Firm* — Lance M. Pritikin(57) **CLAIM**

The ornamental design for a combined rear view camera and brake light assembly, substantially as shown and described.

DESCRIPTION

FIG. 1 is a perspective view of a combined rear view camera and brake light assembly showing my new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof;

FIG. 7 is a bottom plan view thereof; and,

FIG. 8 is a perspective view thereof as applied to a motor vehicle.
 The broken lines are included for illustrative purposes only and form no part of the claimed design.**1 Claim, 4 Drawing Sheets**FIG. 1
